UNITED STATES PATENT OFFICE.

WALTER I. KIRK, OF CHICAGO, ILLINOIS, ASSIGNOR TO LYON & HEALY, OF CHICAGO, ILLINOIS, A CORPORATION OF ILLINOIS.

PEDAL ATTACHMENT FOR PIANOS AND THE LIKE.

1,269,717.

Specification of Letters Patent. Patented June 18, 1918.

Application filed June 3, 1915. Serial No. 31,829.

To all whom it may concern:

Be it known that I, WALTER I. KIRK, a citizen of the United States, residing at Chicago, in the county of Cook and State of Illinois, have invented a certain new and useful Improvement in Pedal Attachments for Pianos and the like, of which the following is a full, clear, concise, and exact description, reference being had to the accompanying drawings, forming a part of this specification.

My invention relates to pedal attachments for pianos and like instruments.

Prominent objects of the invention are to provide a simple and practical device for attachment to or use in connection with a piano pedal so as to permit the pedals to be actuated by children and others having short legs; to simplify the construction and cheapen the cost of manufacture of the device; to arrange for the easy attachment of the device to the piano pedals, and ready detachment of the same therefrom; to permit adjustment to accommodate different styles or kinds of pedals located at different heights; to secure a high degree of efficiency of operation; and to accomplish the foregoing and other desirable results in a simple and expeditious manner.

In carrying out my invention in the manner hereinafter set forth, I provide a frame more or less in the form of a stool which is adapted to be located upon the floor in front of the piano or other instrument in connection with which the device is to be used. At the upper portion of the frame or stool a pair of pedals is provided and these pedals are conveniently pivoted at their forward ends so as to permit them to be swung or operated up and down by the feet. Operating rods are connected with the pedals in the rear of their pivots and are extended down to clips which are adapted to be applied to the pedals of the piano or like device. These clips are of peculiarly advantageous construction to permit them to be readily applied to and detached from the pedals. Thus the device may be set upon the floor in front of the piano or other instrument with its treadles more or less above the piano pedals and its clips may be applied to said pedals so that by operation of the treadles the piano pedals may be actuated as desired.

In the accompanying drawings Figure 1 55 is a vertical section of a pedal attachment embodying my invention taken on line 1—1 in Fig. 2;

Fig. 2 is a plan view of the same;

Fig. 3 is a sectional view of a detail of 60 construction.

Referring to the drawings I show a base or frame A, more or less in the nature of a stool with an upper frame 1, and four upright legs 2—2 and 3—3. The upper 65 frame 1 is conveniently made rectangular in form as shown in Fig. 2, and the legs 2—2 and 3—3 properly secured thereto. The legs 2 and 3 are preferably provided at their lower ends with coverings or tips 4 desirably made of rubber or some similar material. The rear of the frame 1 is provided with rearwardly extending projections 5—5 which are preferably provided with end pieces 6 which may be in the form of plugs 75 made of rubber or similar material inserted in apertures in the projections 5, as shown in cross section in Fig. 2. Two treadles 7—7 are mounted above the frame 1, said treadles being conveniently pivoted at their front 80 ends as shown at 8 (Fig. 1), upon lugs 9—9 formed integral with the frame 1, whereby said treadles may swing up and down (Fig. 1). Operating rods 10 are pivotally connected at their upper ends 11 to the rear 85 portions of the treadles 7. These operating rods 10 are preferably made of two telescoped parts 12 and 13 with a thumb screw 14 to hold said parts in adjustment. Pedal clips 15 are pivoted at 16 to the lower ends 90 of the rods 10. The clips 15 are preferably made so that they may be detachably applied to the pedals, the construction shown consisting of a front portion 15^a adapted to fit around and over the end or toe of the 95 pedal as shown in Fig. 2, and a connected rear portion 17 in the form of a cross bar adapted to fit underneath the shank 18 of the pedal. Thus the pedal is more or less grasped or inclosed, but a side opening is 100 provided between the toe portion 15^a and the heel or cross member 17 through which the pedal may be inserted so as to apply the clip to the pedal and remove it therefrom. The cross or heel member 17 is provided 105 with a screw 19 adjustable in a slot 20 and preferably inclosed in a rubber washer 21 whereby said screw may be adjusted to ac-

commodate different sized shanks for different pedals between said washer or collar 21 and the side connecting portion 22 between the portions 15^a and 16 of said pedal 5 clip.

Thus in using the device it will be set in position in front of the piano as shown in Figs. 1 and 2 with the end pieces 6 in contact with the front wall of the piano and the caps or tips 4 resting upon the floor. The clips 15 will be applied to the piano 10 pedals 25 so as to embrace the same and the rods 10 will be properly adjusted in length so that when the piano pedals are in their 15 normal elevated position, one of which is shown in said position in Fig. 1, the treadles 7 will be elevated and inclined at the angle as is shown by the treadle illustrated in elevation (not in section) in Fig. 1. In this 20 way the feet of the person using the piano may normally and continually rest upon the treadles 7, allowing the same to be held upwardly by the spring action of the piano 25 pedals when desired. When it is desired 30 however, to operate one of said piano 35 pedals the corresponding foot treadle 7 is depressed, as shown by the treadle shown in section in Fig. 1, whereupon the corresponding 40 push rod 10 will depress said piano 45 pedal as shown in Fig. 1. Thus one or the 50 other or both of said piano 55 pedals may be operated from time to time, as desired.

When desired to remove the device from position in front of the piano, the push rods 55 10 may be elevated slightly so as to tip 60 them with reference to the piano 65 pedals whereby they may be disconnected from 70 said 75 pedals by a sidewise movement. Simply 80 lifting the entire device either by lifting 85 the treadle 7 or the supporting frame 1 90 is sufficient to accomplish this disengagement 95 of the clips 15 from the piano 100 pedals.

It will be seen that a person using the attachment requires no separate foot rest, the 45 feet resting always upon the treadles 7; nor 50 is it necessary to move the feet from a foot 55 rest to a pedal actuating mechanism, because 60 obviously the feet by resting upon the treadles 65 7 are always in position to operate the 70 mechanism to actuate the pedals, the treadles 7 75 accommodating both toes and heels 80 of the feet. Furthermore, the connection 85 of the device with the pedals is sufficiently 90 positive to avoid any slipping or disengagement 95 of the device from the piano 100 pedals, but at the same time is such as to permit 105 a quick and ready disconnection from the piano 110 pedals. Furthermore, by connecting the operating rods 10 to the forward ends 115 of the clips 15, said rods will act upon said 120 clips near the forward or outer ends of the 125 pedals, and will therefore exert a strong 130 leverage, much greater of course than if 135 said rods acted upon the toe portions of the 140 pedals or even upon the pedal shanks. This

leverage is further emphasized by the leverage secured by the treadles 7 and their connections with the operating rods 10, substantially in the rear of the points of pivotal support of the treadles, whereby very easy 70 operation of the pedals is obtained.

In order to prevent the treadles 7 from being swung too far upwardly they are preferably provided with set screws 7^a underneath their forward ends which set 75 screws are adapted to come into contact with a shoulder or edge portion of the frame 1. The treadles 7 are preferably made of very light metal such as aluminum and of a single piece with a serrated surface 7^b surrounded by a rim 7^c. 80

It will be understood that changes and modifications may be made without departing from the spirit of the invention.

What I claim is:

1. A device of the class specified comprising in combination a frame adapted to be set in position in front of the piano or other instrument, treadles pivotally connected at their forward ends to said frame, operating rods pivotally connected with said treadles and extended downwardly therefrom in a substantially vertical direction and clips for the pedals of the piano or other instrument, said clips when in position on said pedals 90 grasping the pedals and extending lengthwise of the same to the front ends thereof, said clips being pivotally connected at their forward ends to the lower ends of said operating rods. 95

2. A device of the class specified comprising in combination a frame adapted to be set in position in front of the piano or other instrument, treadles pivotally connected at their forward ends to said frame, operating rods pivotally connected with said treadles and extended downwardly therefrom in a substantially vertical direction and clips for the pedals of the piano or other instrument, said clips when in position on said pedals 105 grasping the pedals and extending lengthwise of the same to the front ends thereof, said clips being pivotally connected in front of the front ends of the pedals to the lower ends of said operating rods. 110

3. A device of the class specified comprising in combination, a rectangular frame consisting of front, rear and side parts, legs extending downwardly from the corners of said frame, projections to contact with the front of the piano formed by continuations of said side parts, treadles pivoted at their forward ends to the front part of said frame, operating rods pivotally connected to the rear end portions of said treadles and extending downwardly therefrom and pedal clips engaging said pedals and connected with the lower ends of said operating rod. 120

4. A device of the class specified comprising a frame provided with supporting legs, 125

- treadles having their front ends pivotally connected with said frame, connecting rods extending downwardly from said treadles and pedal engaging clips grasping said pedals by overlying and partially inclosing the front portions of said pedals and underlying the rear portions of the same, whereby said clips may be disengaged by an elevation of said rods and the device may be detached by lifting it so as to elevate said rods.
5. In a device of the class specified, a pedal engaging clip comprising a member constructed to engage the upper side of the toe portion of the pedal and having an integrally formed cross piece engaging the under side of the pedal remote from the toe portion, said cross piece being provided with an
- 10
- 15

adjustable device for engaging one side of said pedal.

6. In a device of the class specified, a pedal engaging clip comprising toe portions adapted to fit over and at the sides of the toe portion of the pedal, and a cross piece adapted to fit underneath the shank portion of the pedal, said cross piece being provided with a longitudinally extending slot and a screw having a member constructed to engage the pedal adapted to be adjusted in said slot.

In witness whereof, I hereunto subscribe my name this 18th day of May, A. D. 1915.

WALTER I. KIRK.
